UNITED STATES PATENT OFFICE.

FRED S. WELCH, OF PONTIAC, MICHIGAN, ASSIGNOR TO PONTIAC TRACTOR COMPANY,
OF PONTIAC, MICHIGAN, A CORPORATION OF MICHIGAN.

SPRAYING-PUMP.

1,241,178.

Specification of Letters Patent. Patented Sept. 25, 1917.

Application filed January 8, 1916. Serial No. 71,093.

To all whom it may concern:

Be it known that I, FRED S. WELCH, a citizen of the United States, residing at Pontiac, county of Oakland, State of Michigan, have invented a certain new and useful Improvement in Spraying-Pumps, and declare the following to be a full, clear, and exact description of the same, such as will enable others skilled in the art to which it 5 pertains to make and use the same, reference being had to the accompanying drawings, which form a part of this specification.

My invention relates to spraying pumps and an object of my improvements is to provide an improved construction which may be cheaply constructed and easily assembled and disassembled and in which the valves are conveniently accessible for cleaning.

I secure this object in the device illustrated in the accompanying drawings in which,

Figure 1 is an elevation partly in section of an apparatus embodying my invention.

Fig. 2 is a plan view of the same, also 25 partly in section.

Fig. 3 is an elevation looking from the right of Fig. 1, the pressure tank and valve-manifold being removed.

Fig. 4 is a plan view, partly broken away, 30 of the valve manifold.

Fig. 5 is a detail section on the line E—E Fig. 4.

Fig. 6 is a section on the line F—F Fig. 4.

Fig. 7 is a section on the line G—G Fig. 4. 35 *a a* are the cylinders and *a² a²* the plungers operating in the cylinders of a pump *a a*. *f²* is the crank shaft and *f f* the cranks joined to the plungers *a² a²* by connecting rods *g g*. *h* is a worm wheel inclosed in a 40 casing *h²* and keyed upon the shaft *f²*. *i* is a shaft which is rotated by the source of power, for instance, an internal combustion engine. *j* is a worm upon the shaft *i*, its threads engaging the teeth of the worm 45 wheel *h*. *m* is a suction manifold communicating with the intake valve of the pump as hereinafter described by the conduit *m²* and with the spraying fluid by a pipe *k* extending into a reservoir of such fluid, the cover 50 of which is indicated by the reference character *k²*, which cover forms a support for the pump and connecting apparatus. *b* is a pressure tank having a gage *b²* at its upper end to indicate the pressure of the air imprisoned therein, and a delivery pipe *b³* 55 leading to the spraying nozzle.

c is a valve manifold. *d* is a piece of angle iron bent into parallel portions joined by a loop and having one horizontal and one vertical flange. The pump cylinders 60 *a a* are in an integral casting and are secured to, and extend between, the parallel portions of the strap iron *d*. The loop of said iron bends around the pressure tank *b* and at this point, for convenience of construction, the horizontal flange is cut away as shown in Fig. 2. *d² d²* are set screws 65 engaging the strap iron *d* and pressing against the pressure tank *b*.

The valve manifold *c* is placed with the 70 walls surrounding its proper apertures engaging against the intake and discharge orifices of the pump. The pressure tank is then placed in the loop of the strap iron *d* with the walls surrounding the intake aperture, engaging against the wall surrounding the discharge aperture *n* leading from the manifold *c*. The set screws *d² d²* are then set up firmly with a wrench thus engaging 75 all the parts together and completing the assembly of the apparatus.

The walls *n n* of the intake orifices to the cylinders *a a* and the walls *m³* surrounding the delivery end of the suction pipe *m²*, are arranged in approximately the same plane. 80 The valve manifold *c* is provided with apertures *o o* and their surrounding walls are adapted to engage, and form a tight joint with the intake orifices *n n* of the cylinders *a a*. *p* is an orifice through which the 85 spraying fluid enters the manifold *c*. The walls surrounding the orifice *p* are adapted to engage the walls surrounding the orifice *m³*. *u* indicates the passage through which the spraying fluid passes from the manifold 90 *c* to the compression tank *b*.

The manifold *c* is an integral casting, the entrance orifice *p* expands into a cored passage *p²* in the lower part of the manifold and in the upper wall at each end of the 100 manifold is formed a check valve *s*. The intake orifices *o o* communicate with chambers *o²* above the valves *s s*. The chambers *o²* communicate through a non-return check valve *r* with a cored passage *r²* which 105 communicates through a non-return valve *t* with the discharge orifice *u*.

The operation of the pump is as follows:

On the ascent of one of the plungers *a²* the spraying fluid is drawn through the 110 passages *k m²*, the inlet orifice *p*, the passage *p²*, past one of the valves *s* and orifice *o* to

the cylinder a . On the descent of the piston the liquid so drawn into the cylinder is forced back through the orifice o , into the chamber o^2 past a valve r into the passage 5 r^3 past a valve t through the opening u into the pressure tank b .

s^2 indicates plugs closing orifices through which access may be had to the valves s and r^2 r^2 are plugs closing orifices through 10 which access may be had to the valves r r . t^2 is a plug closing the orifice by which access may be had to the valve t .

The passage v opens from the chamber or passage r^3 and is provided with a relief 15 valve v^2 which discharges through a pipe v^3 through an opening k^3 in the supply reservoir cover back into the supply reservoir.

The relief valve v^2 being located between 20 the valves r and t both of which valves open away from the cylinder and toward the compression chamber there is but little loss of liquid when the relief acts to lower the pressure at this place and the action of the piston is not interfered with.

25 Spraying pumps are used with liquids that are somewhat corrosive and liable to form deposits, it is therefore necessary to make the valves accessible for cleaning and repairing. In the above described apparatus the loosening of the set screws d^2 d^2 permits the valve manifold with all the valves therein to be removed which may then be placed in a reservoir of water to soak off the deposit and clean the valves and passages. Each of the valves is accessible 30 through an aperture closed by a screw plug.

The angle iron d is of structural material easily obtained upon the market and forms a strong, cheap, and convenient base for 40 assembling the parts.

What I claim is:

1. In an apparatus of the kind described, 45 an angle iron bent into parallel portions joined by a loop, one flange of the angle iron being horizontal, a pump secured to said parallel portion upon the horizontal flange, and a pressure tank secured in said loop.

2. In an apparatus of the kind described, 50 an angle iron bent into parallel portions joined by a loop, a pump secured to said parallel portions, and a pressure tank secured in said loop, a manifold located between said pump and pressure tank, and means engaging said loop for forcing said tank toward said pump for the purpose described.

3. The combination of a pump, having 55 an aperture with engaging walls, a pressure tank having an aperture with engaging walls, a valve manifold having an aperture, the walls surrounding said aperture engaging walls surrounding said aperture in the

pump, and an aperture having a wall engaging said aperture in the pressure tank, and means for forcing said pump and tank 65 toward each other to form tight joints, at said engaging walls.

4. In an apparatus of the kind described, a manifold having a laterally extending intake passage, a second and third laterally 70 extending passage, a wall above said intake passage, a valve in said wall opening to the second passage, a wall above said second passage in part dividing the same from the outer air and in part dividing the same 75 from the third passage, a valve opening from said second passage to the third passage, the wall above said second passage being provided with an aperture adapted to permit the removal of the valve located between said passage and the intake passage, and a removable means for closing said aperture, a pump having a cylinder and an aperture opening from said cylinder communicating with said second passage, and 85 a discharge orifice leading from said third passage.

5. In an apparatus of the kind described, 90 an angle iron bent in parallel portions joined by a loop one flange of the angle iron being horizontal and cut away at the loop portion, a pump secured to said parallel portions upon the horizontal flange, and a pressure tank secured in said loop.

6. In an apparatus of the kind described, 95 an angle iron bent in parallel portions joined by a loop one frame of the angle iron being horizontal and cut away at the loop portion, a pump secured to said parallel portions upon the horizontal flange, and a pressure tank secured in said loop, a manifold located between said pump and pressure tank, and means engaging said loop for forcing said tank toward said pump for the purpose described. 105

7. In an apparatus of the kind described, 110 an iron bent into parallel portions joined by a loop, a pump secured to said parallel portions, and a pressure tank secured in said loop, a manifold located between said pump and pressure tank, and means engaging said loop for forcing said tank toward said pump for the purpose described.

8. In an apparatus of the kind described, 115 a compression cylinder, a compression chamber, a conduit connecting said cylinder and chamber, two automatic valves in said conduit opening toward said chamber and closing away from said chamber, and a relief valve located between said two valves. 120

In testimony, whereof I sign this specification.

FRED S. WELCH.
